US00D469005S

(12) **United States Design Patent** (10) Patent No.: **US D469,005 S**
 Ellis et al. (45) Date of Patent: ** Jan. 21, 2003

(54) **CAPTIVE SCREW**

(75) Inventors: **Thomas J. Ellis**, Wilmington, DE (US); **Edward A. McCormack**, Chadds Ford, PA (US); **Harry L. Dickerson**, Downingtown, PA (US); **William R. Frame**, Brookhaven, PA (US); **Steven M. Lubeck**, Aldan, PA (US)

(73) Assignee: **Southco, Inc.**, Concordville, PA (US)

(**) Term: **14 Years**

(21) Appl. No.: **29/120,903**

(22) Filed: **Mar. 28, 2000**

CLAIM

The ornamental design for a captive screw, as shown and described.

DESCRIPTION

FIG. 1 is a top plan view of the captive screw showing our new design;

FIG. 2 is a side elevation thereof, the remaining sides being identical;

FIG. 3 is a perspective view thereof;

FIG. 4 is a bottom plan view thereof;

FIG. 5 is a top plan view of the captive screw showing a second embodiment of our new design;

FIG. 6 is a side elevation thereof, the remaining sides being identical;

FIG. 7 is a perspective view thereof; and,

FIG. 8 is a bottom plan view thereof.

The broken lines in the figures are for illustrative purposes only and form no part of the claimed design.
